TOP BURNER ASSEMBLY FOR GAS STOVE
 Albert H. Crone, Rockford, Ill., assignor to Geo. D. Roper Corporation, Rockford, Ill., a corporation of Illinois

Application July 27, 1951, Serial No. 238,919
 9 Claims. (Cl. 126—39)

This invention relates to a top burner assembly for a gas stove.

It is an object of this invention to provide a novel burner and mixer tube which is adapted for use at any top burner location on a gas stove and which is readily removable from the stove with a minimum of disassembly of the other stove parts.

Another object of this invention is to physically support a top burner of a gas stove in a novel manner which improves the transfer of heat from the burner to the cooking pan.

A further object of this invention is to provide a top burner for a gas stove having positive means for insuring a definite spacing between the burner flame ports and a cooking pan mounted above the burner.

Another object of this invention is to provide a novel top burner assembly for a gas stove in which the burner is suspended from the grate, and in which grate rattle is minimized.

A still further object of this invention is to positively locate at predetermined positions relative to one another a top burner of a gas stove and the adjacent end of the flash tube which provides ignition for the top burner, so as to maintain the top burner at all times in igniting relation to the flash tube.

Other and further objects and advantages of the invention will be apparent from the following description of a preferred form thereof.

In the drawings:

Figure 1 is a fragmentary top view of a stove incorporating the present invention.

Fig. 2 is a vertical sectional view of a portion of the stove construction of Fig. 1.

Fig. 3 is a top view of the bracket for locating the top burner and for supporting the adjacent end of the flash tube by which the top burner is ignited.

Fig. 4 is a top view of a pilot burner, the flash tubes extending from the pilot burner, and the supporting brackets for the ends of the flash tubes remote from the pilot burner.

Fig. 5 is a front view, partly in section, of the Fig. 4 assembly.

Fig. 6 is a vertical section of the simmer burner and vertical mixer therefor according to the present invention.

Fig. 7 is a longitudinal section of the grate.

Fig. 8 is a top view of the main burner portion of the top burner according to the present invention.

Fig. 9 is an end view, partly in section, of the main burner of Fig. 8.

In the drawings, the top burners, indicated generally at 1, are shown as being located in staggered relation at the top 2 of a gas stove. Between two of the top burners a pilot burner 3 is located, below the stove top 2. Gas is supplied to the pilot burner through a conduit 4 connected to a gas manifold. Horizontal flash tubes 5 and 6 extend outward from the pilot burner 3 to adjacent the respective top burners for igniting the latter from the pilot burner. Each of the top burners in the illustrated embodiment of the invention is of the two-way type, including a main burner 7 and a simmer burner 8.

As best seen in Fig. 6, the simmer burner includes a hollow bulb 9 provided with a plurality of upwardly

extending arcuate flame ports 10. At its lower end the burner bulb 9 is supported on a hollow vertical mixer tube 11, which has a Venturi shaped interior conduit 12 along its length. At its lower end the mixer tube is formed with a tubular portion 11a having a pair of diametrically opposed air inlet ports 14. A tubular sheet metal member 15 snugly engages the periphery of the tubular portion 11a and is formed with diametrically disposed holes 16 adapted to register, in whole or in part, with the ports 14 to permit the entry of the desired amount of air into the simmer burner mixer tube. An adjustable screw 17 threadedly secured to the mixer tube engages in a horizontal peripheral slot 18 in the tubular member 15 to permit adjustment of the holes 16 relative to the holes 14, for controlling the amount of air entering the simmer burner mixer, and for clamping the tubular member 15 rigidly to the mixer when the desired adjustment has been made. At its lower end the tubular member 15 is formed with an annular inturned portion 19 formed with a central circular hole 20 registering with the interior conduit 12 in the mixer tube. An external boss 21 is formed on the mixer tube 11 toward the upper end thereof and provides a charging port 22 for supplying gas to the flash tube, as will appear hereinafter.

For physically supporting and locating the simmer burner a generally U-shaped bracket assembly, indicated generally at 23, is provided. This bracket at its lower end carries a vertically extending spud 24 which extends upwardly through the hole 20 into the mixer tube 11 to supply gas thereto. A conduit 25 connected to the manually operated main shut-off valve for the top burner communicates with the simmer burner spud to furnish gas thereto. The lower arm 26 of the bracket is suitably secured, as by a screw 27, to the lower wall 28 of the burner box to be supported thereby. Spaced lugs 29a and 29b formed on the lower bracket arm 26 extend through corresponding holes in the bottom 28 of the burner box to locate the bracket 23 properly with respect to the corresponding burner hole in the stove top.

An L-shaped arm 29 of the bracket extends upwardly and at its upper end supports a pair of identical horizontal arms 30 for supporting the flash tube.

The flash tube assembly is of integral cast iron construction and includes a central ring portion 31 disposed around the pilot burner tube 32. A depending curved rib 33 carries a central ring 34 for locating the pilot burner tube centrally of the flash tube ring 31. On either side of the ring 31 is a cylindrical flash tub 35 extends horizontally. Integral with the free end of each flash tube are a pair of transverse horizontal arms 36. These arms are formed with apertures 37 adapted to be aligned with threaded apertures 38 formed in the top face of each of the respective bracket arms 30. Screws 40 serve to clamp the arms 36 and 30 together so that the bracket 23 physically supports the flash tube in the desired manner.

Spaced horizontal arms 41 extend outwardly in parallel relation from the arms 36 and are joined at their free ends by a ring 42 to form a simmer burner support member. Diametrically opposed channels 43 are formed in the upper face of ring 42, and a vertical channel 44 is formed in the inner face of the ring intermediate the channels 43.

The simmer burner mixer tube 11 is formed with outwardly protruding, diametrically opposed horizontal lugs 45 adapted to register respectively with the channels 43 and is also formed with an outwardly protruding lug 46 adapted to register with the channel 44. When assembled, the simmer burner mixer tube 11 extends upward through ring 42 with lugs 45 resting on the horizontal channels 43 and lugs 46 seated in the vertical channel 44. In this position of the simmer burner mixer

11 its charging port 22 discharges a jet of combustible air-gas mixture into the open free end of the flash tube to be ignited by the pilot burner and flash back to ignite the main air-gas stream in the internal conduit 12 passing to the simmer burner head 9.

Thus, it will be seen that the bracket 23 physically supports the flash tube at one end and positively locates the simmer burner mixer at the desired height and angular relationship with respect to the flash tube so as to receive ignition therethrough, as well as physically supporting the simmer burner and its mixer and locating the same in communication with the gas supply.

An identical bracket 23a supports the free end of flash tube 6 and locates the simmer burner 8a relative thereto in the same manner.

The main burner 7 is located in communication with a vertically extending spud 47 attached to the lower bracket arm 26 and communicating through a passage 48 therein with a conduit 49 leading from the manually-operated main shut-off valve for the top burner. The main burner assembly includes a vertically extending mixing tube having a Venturi-shaped passage 50 which branches off toward its upper end to provide two separate upwardly-extending passages communicating with an annular horizontal passage 51 extending completely around the main top burner. A plurality of flame ports 52 are formed in the peripheral side wall 53 of the burner head and communicate with the annular passage 51 to discharge gas therefrom. The burner side wall 53 is inclined downwardly and inwardly at an angle of 15 degrees and the flame ports 52 extend at right angles thereto. In this manner the upper portion of the peripheral side wall 53 overhangs the flange ports 52 and prevents spillovers by the cooking pan from entering into the flame ports. A plurality of radial slots 66 are formed in the top wall of the main burner and extend from the radially inner edge of the main burner to a point adjacent the flame ports 22 to provide gas discharge passages for cross igniting the main burner ports from the simmer burner 8.

At its lower end the main burner mixing tube is formed with spaced air holes 79 and carries an apertured tubular member 80 which is adjustable to control the air supply to the main burner in a manner similar to the described arrangement for the simmer burner.

Formed integral with the burner to extend above the top thereof are three horizontal radially-extending ribs 54, 55, 56 which terminate in heads 57, 58, 59 beyond the periphery of the burner. At their extreme outer ends on their lower faces these heads are formed with flat horizontal seating surfaces 60, 61, 62.

The stove top 2 at each of its bowl pan portions is formed with an annular downwardly depressed portion 63 forming a flat ledge surrounding each of the holes in the stove top for receiving the burners. Each of the ledges 63 is formed with three evenly spaced holes 64. Each burner bowl 65 is generally dish-shaped in configuration and extends downwardly and inwardly from the ledge 63.

The burner grate includes a ring 69 provided with three evenly spaced radial arms 70 each having an outwardly protruding portion 71 extending above the top face of the ring. The radially inwardly-extending portions of the arms 70 also extend above the top face of the ring and provide horizontal flat surfaces 72 for supporting a cooking pan. Each of the outer protrusions 71 is formed with a flat lower face 73 which rests on the stove top 2. The outer vertical side wall 74 of ring 69 is adapted to seat snugly against the side wall 75 which joins the stove top 2 and the depressed ledge 63. Depending lugs 76 are formed integral with the ring 69 and extend through the holes 64 to assemble the grate on the stove top.

Intermediate the grate arms 70 there are formed three radial arms 77 which extend inward horizontally in spaced relation above the top face of ring 69. At their inner ends the arms 77 are cut away to form flat horizontal seating surfaces 78. These surfaces 78 form seats for

the surfaces 60-62 on the radially extending burner arms 57-59, so that the burner 7 is physically supported by the grate in this manner. From Fig. 2 it will be noted that the flat top surfaces of the top arms 54-56 on the main burner are on a level with the top surfaces 72 on the grate. Since the cooking pan rests on these surfaces, it will be seen that the top of the main burner directly contacts the cooking pan and heats the latter by conduction, along with the convection heat from the flames at the main burner.

Because the top surfaces of the main burner itself define the level of the bottom of the cooking pan it is also evident that the burner flame ports 52 have a fixed and definite relationship to the pan bottom. This factor is of the utmost importance in obtaining the optimum heating effect from the burner.

Since the main burner is suspended from the grate, the weight of the burner acts to maintain the grate stable and to eliminate grate rattle.

With the novel "drop through" construction of the top burner according to the present invention, the top burner may be installed at any burner location on the stove top. Since the burner mixers extend vertically there is no problem of shaping the mixers to occupy particular positions on the stove top, front or rear and left or right. Also, the main burner can be removed merely by lifting the associated grate above the stove top. The simmer burner can be removed through the burner hole 79 in the bowl pan portion 65 after the main burner has been removed.

While there has been disclosed a preferred form of the present invention it is to be understood that various changes from the specific illustrated form may be resorted to without departing from the spirit and scope of the invention.

I claim:

1. In a top burner assembly for a gas stove, in combination, a horizontal flash tube adapted to communicate at one end with a pilot burner, a support member connected to the flash tube and extending beyond the other end thereof, a bracket supporting said support member and said other end of the flash tube, means for mounting said bracket on a stove, a straight elongated upwardly extending burner mixer formed with a discharge port for receiving ignition through the flash tube from the pilot burner, and means on said burner mixer engaging said support member which extends beyond the flash tube to releasably support said burner mixer thereon and permit axial withdrawal of the mixer from the support member and to align said discharge ignition port of the mixer with said other end of the flash tube.

2. In a top burner assembly for a gas stove, in combination, a horizontal flash tube adapted to communicate at one end with a pilot burner, a support member connected rigidly with the flash tube and extending outward beyond the other end thereof and terminating in a horizontally disposed ring, a bracket connected to said support member to support the latter and said other end of the flash tube, means for mounting said bracket on a stove, and a mixer for a burner extending upwardly through said ring on the support member and formed with a transverse discharge port for receiving ignition through the flash tube from the pilot burner, said mixer being formed with outwardly protruding transverse lugs resting on the top of the ring to support the mixer thereon, and a vertical channel formed in said ring and an outwardly protruding transverse lug formed on said mixer snugly seated in said channel to align the discharge ignition port of the mixer with said other end of the flash tube.

3. In a top burner assembly for a gas stove, in combination, a cast iron horizontal flash tube adapted to communicate at one end with a pilot burner, a horizontal support member cast integral with the flash tube and extending outward beyond the other end thereof and terminating in a horizontally disposed ring, an upwardly

extending bracket connected to the bottom of said support member to support the latter and said other end of the flash tube, means for mounting the bracket on a stove, a cast iron mixer for the simmer burner extending vertically through said ring on the support member and formed with a transverse discharge port for receiving ignition through the flash tube from the pilot burner, said mixer being formed with integrally cast transverse lugs protruding outwardly to rest on the top of the ring to support the mixer thereon, and a vertical channel formed in said ring and an integral cast lug on said mixer protruding outwardly therefrom seated snugly in said channel to align the discharge ignition port of the mixer with said other end of the flash tube.

4. In a top burner assembly for a gas stove, in combination, a horizontal flash tube adapted to communicate at one end with a pilot burner, a support member connected to the flash tube and extending outward beyond the other end thereof, an upwardly extending burner mixer formed with a discharge port for receiving ignition through the flash tube from the pilot burner, said support member which extends beyond the flash tube supporting the burner mixer to align the discharge ignition port thereof with said other end of the flash tube, a bracket formed with an upwardly extending arm supporting said support member and said other end of the flash tube, means for mounting said bracket on a stove, said bracket also being formed with an integral lower arm, and an upwardly extending burner spud mounted on said lower arm and supplying gas to said mixer at the lower end thereof.

5. In a top burner assembly for a gas stove, in combination, a horizontal flash tube adapted to communicate at one end with a pilot burner, a support member connected rigidly with the flash tube and extending outwardly beyond the other end thereof and terminating in a horizontally disposed ring, a mixer for the simmer burner extending upwardly through the ring on the support member and formed with a transverse discharge port for receiving ignition through the flash tube from the pilot burner, said mixer being formed with outwardly protruding transverse lugs resting on top of the ring to support the mixer thereon, said ring being formed with a vertical channel and said mixer being formed with an outwardly protruding transverse lug snugly seated in said channel to align the discharge ignition port of the mixer with said other end of the flash tube, an integral bracket including an upwardly extending arm connected to said support member at the bottom thereof to support the latter and said other end of the flash tube and including a horizontal lower arm, means for mounting said bracket on a stove, and an upwardly extending burner spud carried on said lower bracket arm supplying gas to the mixer at the lower end thereof.

6. A top burner assembly on a gas stove comprising an annular main burner having a plurality of main burner ports, a mixer for said main burner depending therefrom eccentrically of the axis of said main burner and having the lower end thereof laterally offset from the axis of the main burner, a simmer burner separate from the main burner, a straight elongated mixer for said simmer burner extending axially thereof, bracket means on the stove for detachably supporting said simmer burner and mixer coaxially of said main burner, first and second upwardly extending burner spuds mounted on said bracket means to extend respectively into the lower ends of the mixer on the simmer burner and the mixer on the main burner, the mixer on said simmer burner having a discharge port therein, a flash tube adapted to communicate at one end with a pilot burner, and means on said bracket means for supporting the other end of said flash tube in alignment with said discharge port to receive ignition through said flash tube and effect ignition of said simmer burner, said main burner having a gas discharge passage formed therein and extending from the radially

inner edge thereof to a point adjacent the main burner ports to produce a gas stream for igniting the main burner ports from said simmer burner.

7. The combination of claim 6 wherein said main burner overlies the simmer burner, and means for removably suspending the main burner on the stove top.

8. In a top burner assembly on a gas stove, the combination of a top burner grate adapted to be supported on the stove top, an annular main burner suspended from said grate and having a mixer depending therefrom eccentrically of the axis of the main burner with the lower end of the mixer laterally offset from the axis of the main burner, a bracket attached to the stove and having a burner spud thereon extending into the lower end of the mixer, a second burner spud on said bracket disposed in axial alignment with said main burner, a simmer burner having an elongated mixer extending axially therefrom, said mixer for the simmer burner having a discharge port therein, a flash tube, an upwardly extending arm on said bracket, means on said arm for supporting one end of the flash tube and for supporting the simmer burner concentric of said main burner with the discharge port in the simmer burner aligned with said flash tube to receive ignition through said flash tube and effect ignition of the simmer burner, said main burner having a gas discharge passage therein extending from the radially inner edge thereof to a point adjacent the main burner ports for igniting the latter from said simmer burner.

9. In a top burner assembly on a gas stove, in combination, a burner grate supported on the stove top and including a plurality of inwardly extending arms, an annular main burner having a plurality of annularly spaced main burner ports and provided with projecting portions connected at its upper side resting directly on said grate arms to suspend the main burner from the grate, a mixer depending from the main burner eccentrically of the axis thereof and having a fuel passage communicating therewith, a horizontal flash tube adapted to communicate at one end with a pilot burner, a support member connected to the flash tube and extending beyond the other end thereof, a bracket formed with an upwardly extending arm connected to said support member to support the latter and the other end of said flash tube, a simmer burner, a mixer depending from the simmer burner and formed with a transverse discharge port, said support member which extends beyond the flash tube supporting said simmer burner with the discharge port thereof aligned with the flash tube to receive ignition through the flash tube and effect ignition of the simmer burner, said bracket also being formed with a lower horizontal arm, an upwardly extending burner spud carried on said lower bracket arm communicating with the mixer for the simmer burner at the lower end thereof to supply gas to the simmer burner, means mounting said bracket on the stove to position said simmer burner axially of said main burner, and a second upwardly extending burner spud carried on said lower bracket arm communicating with the mixer for the main burner at the lower end thereof to supply gas to the main burner, said main burner having a gas discharge passage formed therein and extending from the radially inner edge thereof to a point adjacent the main burner ports for igniting the latter from said simmer burner.
